UNITED STATES PATENT OFFICE.

LOUIS S. JONES, CARL G. HENRIKSON, AND GARFIELD W. FISHER, OF ANDERSON, INDIANA, ASSIGNORS, BY MESNE ASSIGNMENTS, TO THE NATIONAL TILE COMPANY, OF ANDERSON, INDIANA, A CORPORATION OF OHIO.

MECHANICAL SHAKER FOR CERAMIC TILE.

Application filed April 4, 1925. Serial No. 20,823.

Our said invention relates to mechanical shakers for ceramic tiles and it is an object thereof to provide means for mounting a group of tiles in predetermined relation to each other, the retaining means being here shown as consisting of so-called mounting boards having spaces for the tiles with ridges between them.

A further object of the invention is to provide means for agitating the boards in different directions to settle the tiles in their respective cells, with means for varying the amount of such agitating movement.

A further object of the invention is to provide a shaking table for the mounting boards upon which the boards can be placed while the machine is in motion and from which they can also be removed without stopping the machine.

Referring to the accompanying drawings, which are made a part hereof and on which similar reference characters indicate similar parts,

Figure 1 is a transverse vertical section of the machine,

Figure 2, a section on line 2—2 of Fig. 1,

Figure 3 a section on line 3—3 of Fig. 1 with some parts of the machine omitted,

Figure 4, a section on line 4—4 of Fig. 1,

Figure 5, a plan view of the machine,

Figure 6, a section on line 6—6 of Figure 1,

Figure 7, a perspective of the mounting board,

Figure 8, a full size detail section of mounting board,

Figure 9, a full size illustration of one type of tile used,

Figure 10, a detail of a yieldable connection in Fig. 1, on an enlarged scale.

Figure 11, a vertical section through the feeding hopper, a fragment of which is shown in Fig. 2, and

Figure 12, a similar section at right-angles to Fig. 11.

The framework of the machine, as shown, is made up of a base plate 11 interconnected through cross-bars 12 with uprights 13, 13 and 14, 14, the two uprights 14, 14 are connected by a cross-member 15 and the two uprights 13, 13 are connected by a cross-member 16. Uprights 13 are connected to up-

rights 14 at their upper ends by angle irons 17.

Upon angle irons 17 are mounted brackets 18 in which two separate and distinct shafts 19, 19 are slidably and rotatably mounted, the two shafts 19 being alined on one common axis. On each shaft 19 are mounted and fastened two brackets 20 which serve to support a shaker-board 21 which is provided with cleats 22. Between the inner ends of shafts 19 is the upper end of a rocker-arm 23 which rocks on a pin 24 mounted in a bracket 25 which is carried on cross-member 15. The lower end of rocker-arm 23 is provided with a slot 26 in which operates a block 27; block 27 is rotatably mounted on a bushing 28 which is clamped by means of a T-bolt 29 to a slotted crank-disk 30 carried on a shaft 31. Bushing 28 may be clamped at different distances from the center line of shaft 31 thereby varying its throw and thereby varying the amount of endwise movement of shaker-board 21 as well as its speed of movement. Shaft 31 is carried in bearings 32 which are supported by a bar 33 on two of the cross-bars 12. Shaft 31 is driven through pulleys 34 and belt 35 from any suitable variable speed mechanism, as shown in the drawings.

A tilting or rocking oscillatory movement is imparted to the shaker-board 21 by the following mechanism: At one edge of the board is fastened a helically grooved stub 36 over which is wound a flexible member, such as a spring 37, so that this flexible member will transmit to the shaker-board 21 the motion imparted to the flexible member by a sliding rod 38 without interfering with the longitudinal reciprocating or shaking movement of the board. The sliding rod 38 is carried in bearing blocks 39 which are bolted to cross-member 16 and is grooved at its upper end in a similar manner to stub 36 and over it is wound the lower end of spring 37. The sliding rod 38 is connected through pin 38' and connecting rod 40 to a crank pin 41 which is clamped to a slotted crank 42 in such a manner that the distance from the center of pin 41 to the axis of the crank 42 may be adjusted to vary the degree and the speed of oscillation of the shaker-board. Crank 42 is carried on shaft 43

which is mounted in bearings 44 and is driven through pulley 45 and belt 46 from any suitable variable speed mechanism, as shown on the drawings.

5 To protect the working mechanism of the machine it is provided with a boxing 47.

Referring to Fig. 5, the shaker-board 21 is provided at one edge with a metal strip 48, and at the other edge with a series of 10 friction springs 49, 50 and 51, which serve to retain mounting boards 52, 53 and 54, these three being part of a great number of 15 mounting boards used in connection with this machine. These boards are provided with cleats 55 which straddle the shaker-board 21, as can be seen in Fig. 1. Further details of the mounting boards are herein-after described.

In the operation of this machine according to the embodiment of the invention herein illustrated and described, tiles are fed 20 from a hopper 56' onto a mounting board, e. g. board 54, which has been placed on shaker-board 21 by being slid onto the end 25 of the same and is held thereon by friction spring 49 bearing against one of the cleats 55. After being loaded, this board is moved farther along the shaker-board 21 in the direction of the arrow, so that its cleats 30 straddle friction spring 50 and in its place is slipped another mounting board 53 which upon being loaded is shoved over friction spring 50, the mounting board 54 being shoved ahead of it and over friction spring 35 49; in the place of mounting board 53 the mounting board 52 to be filled next is now placed under the hopper and at this time mounting board 54 is removed by being slid 40 off the other end of shaker-board 21, it having been on a sufficient length of time to permit the tile to be distributed over it and to settle into the pattern which may be outlined on the mounting board, thus completing 45 one cycle of operation.

During the shaking operation some of the tiles fall over the edges of the boards and for the purpose of reclaiming these the machine is provided with a hopper construction 56 consisting of sides 57, ends 57' and 50 dividing ridges 58 and 59 which conduct the tile thus spilled through openings 60 under which may be placed suitable receptacles into which they may fall.

Referring to Figs. 7 and 8, the mounting board, as used with this machine, consists 55 of a flat member 61 forming the main body of the board. Around the top edge of the board is fastened a raised border 62, the thickness of which is approximately the same 60 as the thickness of the tiles mounted thereon. A tile such as is shown in Fig. 9 and designated by the number 63 finds its way while being shaken onto the board into one of the numerous outlines patterned on the 65 board by thin strips of metal 64 which are

secured on the top face of the board 61, and the tiles are held in place by these strips until the shaking operation has disposed of any surplus tiles which have been dropped thereon from hopper 56', the borders 62 permitting these to slide off. 70

The shaker-board is shown as being tapered at both ends for convenience in putting on and taking off the mounting boards while the device is in operation, this being 75 an important feature of the invention which, however, may be attained in other ways.

Figures 11 and 12 are vertical sections of the feeding hopper indicated generally at 56' in Fig. 2, such sections being taken at right 80 angles to each other. This feeding hopper is supported on posts 65 in any desirable or convenient manner. The hopper comprises beams 66 supporting inclined side pieces 67 and beams 68 supporting perforated inclined 85 side pieces or screens 69 spaced from the parts 67. At their lower ends the inclined sides 67 and 69 merge respectively at two sides of the hopper into vertical depending members 70 and 71 separated by inclined 90 floor pieces 72 for carrying off dirt and fragments of broken tiles passing through the screens 69. Similarly inclined pieces 73 extend along the other two sides for carrying off refuse passing through the screens 69 adjacent to them. This refuse may fall into 95 any convenient containers for removal at appropriate times.

The bottom of the hopper comprises a perforated section or screen 74 pivoted at 100 one side, as indicated at 75, that has secured thereto at its opposite side a movable chute 76 which coacts with a fixed chute 77 for carrying off screenings of dirt and dust and fragments of broken tiles passing through 105 the screen 74. The screen 74 and the movable chute 76 are positioned as shown in Figure 12, when the machine is standing still or when for any reason the shaker-board 21 is not being operated, at which time tiles may, 110 however, be placed in the hopper. When the tiles are to be permitted to pass to the shaker-board the chute and the screen attached thereto are moved about the pivot 75 by means of a lever 78, into the position 115 indicated in dotted lines in Fig. 12.

It is to be understood that tiles of widely varying shapes and sizes may be mounted on boards by machines constructed according to our invention, which again may be varied in 120 many respects and for various purposes, all without departing from the spirit of the invention and therefore we do not limit ourselves to what is shown in the drawings and described in the specification but only as indicated in the appended claims.

Having thus fully described our said invention what we claim as new and desire to secure by Letters Patent, is:

1. The combination of means for support- 130

ing a mounting board for tiles, means for rocking the board, means for varying the speed of the rocking motion including a lever connected to the supporting means, a 5 crankshaft, a crank adjustably mounted thereon, and connections between the crank and the lever, substantially as set forth.

2. The combination of means for supporting a mounting board for tiles, means for 10 rocking the board, means whereby the speed of the rocking motion may be varied including a crankshaft, a crank of adjustable length mounted thereon, and a yielding pitman connected to the crank and the 15 supporting means, substantially as set forth.

3. In combination a shaker-board pivoted at one edge, a hopper for feeding tiles to the same, parallel shafts beneath the shaker-board, connections from one shaft for reciprocating the board, and yielding connections from the other for rocking it about its pivot, substantially as set forth.

4. A device as in claim 3, with change-speed gearing common to said shafts, substantially as set forth.

5. The combination of means for supporting a mounting board for tiles, means for shaking the board, means for feeding loose tiles to said board, and means for collecting tiles shaken off the board, substantially as set forth.

6. In a tile-mounting machine, a shaker-board, means thereon for guiding a plurality of mounting boards for movement 35 along the shaker-board, and means for preventing accidental movement of said mounting boards, substantially as set forth.

7. In a tile-mounting machine, a shaker-board reduced at its ends, means thereon for 40 guiding a plurality of mounting boards for movement along the shaker-board, and means for preventing accidental movement of said mounting boards, substantially as set forth.

45 8. In a tile-mounting machine, a shaker-board tapered at its ends for ready placing and removal of tile-mounting boards by

a movement of such mounting board lengthwise of the shaker-board, substantially as set forth.

9. The combination of means for supporting a mounting board for tiles, a hopper above the board, means for shaking the board to distribute the tiles over the same, and means for collecting tiles shaken off the 55 board, substantially as set forth.

10. The combination of means for supporting a mounting board for tiles, a hopper positioned to feed tiles to said means, said hopper having imperforate outer walls, 60 perforated inner walls for the hopper spaced from said outer walls, and means for carrying off refuse passing through said perforated inner walls, substantially as set forth.

11. The combination of means for supporting a mounting board for tiles, a hopper positioned to feed tiles to said means, said hopper having imperforate outer walls, perforated inner walls for the hopper spaced from said outer walls, and means for carrying off refuse passing through said 70 perforated inner walls including chutes extending across the space between said outer and inner walls at the lower end of the 75 hopper, said chutes terminating beyond said board supporting means, substantially as set forth.

12. In a tile mounting machine, a shaker board, guides thereon, a plurality of mounting boards held by the guides, and a hopper above one end of the shaker board, said 80 guides being arranged to permit movement of the mounting boards along the shaker board away from the hopper end, substantially as set forth.

In witness whereof, we have hereunto set our hands at Anderson, Indiana, this 2nd day of March, A. D. nineteen hundred and twenty-five.
